(57) **CLAIM**

An ornamental design for packaging for an edible product, as shown and described.

DESCRIPTION

FIG. 1 is a front elevation view of packaging for an edible product;

FIG. 2 is a front plan view of packaging for an edible product shown in FIG. 1;

FIG. 3 is a rear plan view of packaging for an edible product shown in FIG. 1;

FIG. 4 is a side view of packaging for an edible product shown in FIG. 1;

FIG. 5 is the opposing side of the view of packaging for an edible product shown in FIG. 4;

FIG. 6 is a top view of packaging for an edible product shown in FIG. 1; and,

FIG. 7 is a bottom view of packaging for an edible product shown in FIG. 1.

The broken lines representing a candy cane and interior pouch are for illustrative purposes only and form no part of the claimed design.

It is understood that the claimed design is shown as solid line disclosure, including the transparent wrapping covering the candy cane.
